UNITED STATES PATENT OFFICE.

GEORGE W. HARMER, OF PHILADELPHIA, PENNSYLVANIA.

STORM-PROTECTOR.

SPECIFICATION forming part of Letters Patent No. 554,121, dated February 4, 1896.

Application filed October 22, 1895. Serial No. 566,487. (No model.)

To all whom it may concern:

Be it known that I, GEORGE W. HARMER, a citizen of the United States, residing at Philadelphia, in the county of Philadelphia and 5 State of Pennsylvania, have invented certain new and useful Improvements in Storm-Protectors, of which the following is a specification.

My invention relates to a new and useful 10 improvement in storm-protectors and heating apparatus for persons, such as motormen, who are exposed to the elements, and has for its object to provide such a device that will thoroughly protect a person against the inclem- 15 ency of the weather, and which, while permitting free movements of the body, will impart sufficient artificial heat thereto to render such person comfortable at all times.

With these ends in view the invention con- 20 sists in the details of construction and combination of elements hereinafter set forth, and then specifically designated by the claims.

In order that those skilled in the art to 25 which my invention appertains may understand how to make and use the same, I will describe its construction and operation in detail, referring by number to the accompanying drawings, forming a part of this specification, and in which—

30 Figure 1 represents a man enveloped by my improved protector, in connection with the heating apparatus, which is shown in dotted lines; Fig. 2, a central vertical section of the protector; Fig. 3, a detailed perspective of the 35 jacket for maintaining a space between the protector and the body of the wearer; and Fig. 4 is a section of the heating apparatus.

Similar numbers denote like parts in the 40 views of the drawings.

45 1 represents the protector, which may be made of any suitable material, such as rubber-faced fabric, and of a shape best adapted to the particular occupation in which the wearer is engaged. I have shown the protector in this case as having sleeves 2 and a collar 3, which projects up to the ears and nose.

40 4 is a jacket, formed of loosely-woven wire, so as to permit the free circulation of air through its meshes, and at the same time, 50 when upon the wearer, to support the protec-

tor at a slight distance from the body of said wearer. I prefer to form this jacket without sleeves and with a collar 5, having a strap 6, by which it is secured around the throat, and also a strap 7, by means of which it is secured 55 around the body of the wearer.

The heating apparatus is composed of a shield 8, sufficiently concaved upon the inner side to receive a lamp 9, and hinged to this shield at 10 is a semicircular band 11, pro- 60 vided with a bottom 12. 13 is an opening through the front of the shield, by which air is fed to the lamp for the purpose of supporting the flame.

The use of my improvement is as follows: 65 The heating apparatus is placed upon the platform of a car, in proper relation to the brake and bell mechanism, when the lamp is lighted, and the motorman, after donning the protector, stands upon the bottom of the 70 heater within the band. Thus it will be seen that the heat generated by the lamp will flow upward, around the body of the motorman, inside of the protector, and finally issue 75 through the collar, around the neck, and through the sleeves around his wrists. By this arrangement it will be seen that as much heat may be imparted to the body of the wearer as is desired by regulating the flame 80 of the lamp.

14 is an opening in the side of the heater, through which any suitable lever may pass, for the purpose of operating the brake-pawl, or the brake-pawl itself may project through this opening. Other openings may be made 85 in the heating apparatus, so as to give the motorman access to other levers or mechanisms, which may be essential to the controlling of the car.

In practice I have found that a very small 90 lamp will supply sufficient heat to render a motorman entirely comfortable in the severest of weather, and as the expense is trifling and the motorman is left with the free use of his body it will be seen that my improvement 95 provides a very desirable and useful device.

The object of the band 11 being pivoted to the shield is that when the protector is out of use it and the jacket may be folded and placed within the shield and held therein by 100

closing the band thereon, thus producing a small and convenient package for transportation.

I am aware that many slight modifications might be made in my improvement as herein shown and described without departing from the spirit of my invention, which rests in the broad idea of providing a protector which shall act as a flue for the upward passage of heat generated by any suitable apparatus to warm the body of a person wearing said protector.

Having thus fully described my invention, what I claim as new and useful is—

15 1. In a device of the character described, a protector adapted to the body of a wearer, in combination with a spacing-jacket, by means of which free circulation of air is permitted between the body of the wearer and the pro-

tector, and a heating apparatus for generating heat within said protector, substantially as and for the purposes set forth.

2. In a device of the character described, a protector 1, having sleeves 2, and standing collar 3, in combination with a spacing-jacket 25 4, composed of woven wire, and a heating apparatus, consisting of a shield adapted to receive and protect a lamp, and a band pivoted thereto, substantially as and for the purposes set forth.

In testimony whereof I have hereunto affixed my signature in the presence of two subscribing witnesses.

GEORGE W. HARMER.
